UNITED STATES PATENT OFFICE.

WILLIAM C. PEET, OF JERSEY CITY, N. J., ASSIGNOR TO THE J. L. MOTT IRON WORKS, OF NEW YORK, N. Y.

DESIGN FOR A SINK.

SPECIFICATION forming part of Design No. 12,173, dated February 15, 1881.

Application filed December 27, 1880. Term of patent 7 years.

To all whom it may concern:

Be it known that I, WILLIAM C. PEET, of Jersey City, in the county of Hudson and State of New Jersey, have invented or produced a new and original Design for Sinks, of which the following is a specification.

This design relates to the ornamental appearance of the back, body, and legs of the sink, as represented in the accompanying picture.

The back *a* of the sink is of an oblong form, having a central pediment, *b*, and molded upper corners at *c*, in which corners there are leaflet ornaments *d*.

The covering portions *f* for the water-pipes, below the faucets, are angular and molded at the base, and the portions *e* are convex and ornamented with leaflets.

The body of the sink is made with a rolled-over edge, *g*, a cove at *h*, and rounded lower edges at *i*, and the surface is ornamented with leaflet and scroll ornaments, as shown.

The legs are round and tapering and have coves and beads at *k l n*, a foot at *o*, fluting at *r*, and scroll ornaments at *s*.

25

I claim as my invention—

1. The design for the back of a sink, consisting of the oblong molded edge *c*, pediment *b*, leaflet ornaments *d* and *e*, and angular projections *f*, substantially as described and represented. 30

2. The design for the body of a sink, consisting in the rolled-over edges, coves *h*, rounded edges at *i*, and ornament leaflets, substantially as described and shown. 35

3. The design for the tapering sink-legs, composed of the coves, beads, flutes, and feet, substantially as described and represented.

Signed by me this 23d day of December, A. D. 1880.

WM. C. PEET.
